Attorney.

UNITED STATES PATENT OFFICE.

HARRY B. PALMER, OF MORRISTOWN, NEW JERSEY.

TOY GUN.

1,232,384.

Specification of Letters Patent.

Patented July 3, 1917.

Application filed August 20, 1915. Serial No. 46,521.

To all whom it may concern:

Be it known that I, HARRY B. PALMER, a citizen of the United States, and a resident of Morristown, in the county of Morris and State of New Jersey, have invented certain new and useful Improvements in Toy Guns, of which the following is a specification.

This invention relates to a toy gun and particularly to a toy gun for firing strip ammunition, such as wooden or other projectiles detachably connected to a projectile-strip and adapted to be driven therefrom, as by the action of a hammer controlled by a rapid-fire movement.

The preferred construction is one in which a single controlling element or handle governs the feeding of the projectile-strip and also the firing action; that is, the movement of the hammer or firing-pin back and forth, to bring about the detachment and discharge of projectiles from said strip. In said construction there is a definite predetermined relation between the feed of the projectile strip and the action of the hammer or firing-pin.

Specifically, the preferred form of gun embodying my present invention is one in which the breech of the gun has transverse breech and feed openings of different dimensions through the latter of which the strip is adapted to pass freely and in the former of which successive projectiles are adapted to be stopped and lodge momentarily until driven from the gun by the action of the firing mechanism.

An important specific feature of my present invention is the provision of a single combined feeding and firing device, preferably rotary, by means of which successive projectiles of the strip are fed to firing position in the breech and movement then imparted to the firing device for discharging the positioned projectiles in rapid succession.

Other features of my invention not hereinbefore referred to will be hereinafter described and claimed and illustrated in the accompanying drawings, in which—

Figure 1 is a side elevation of a toy rapid-fire gun illustrating my present invention.

Fig. 2 is a plan of the same.

Fig. 3 is a cross section in line 3—3, Fig. 1.

Fig. 4 is an elevation of a portion of the

gun viewed from the side opposite that shown in Fig. 1.

Figs. 5 and 6 are details of the controlling crank or handle.

Figs. 7 and 8 are details of the reel for the strip.

Similar characters designate like parts in all the figures of the drawings.

My invention may be embodied in any suitable gun and operating mechanism for carrying out the objects hereinbefore stated and more particularly set forth in the claims. In the preferred construction the gun is in cannon form embodying a relatively long barrel, 2, having a suitable way or bore, 3, through which projectiles may be discharged. This bore in the construction illustrated extends from one end of the gun to the other and co-operates at the breech thereof with means for feeding and firing projectiles. The barrel proper may be mounted on any suitable type of support, such as the open frame 4, which in turn is usually mounted on legs, such as a tripod 5.

My present invention differs from others in this art with which I am familiar mainly in that it employs a projectile-strip, for feeding projectiles to firing position in the gun, and firing means for detaching these projectiles from the strip and driving them from the gun. The preferred construction shown is one in which the strip is fed at a fairly rapid rate and the projectiles are detached and discharged therefrom with a rapid-fire action.

In the specific embodiment of the invention illustrated, the way or bore 3 through which the projectiles are discharged is intersected at the breech of the gun by a breech-opening, 6, of sufficient length, measured in the direction of the bore of the gun, to admit and locate a single projectile, and this breech-opening, which constitutes also a path for the movement of the feed-strip, is also intersected in turn by a feed-opening proper, designated by 7, much shorter in the direction of the length of the gun than is the breech-opening 6. As both of these openings are disposed crosswise of the gun and intersect the way or bore 3 and are also disposed in line with and immediately adjacent to each other, a stop wall 8 of considerable length in the direction of the bore

of the gun is formed, against which successive projectiles carried by the strip strike and by which they are stopped and located in position crosswise of the gun. Of course 5 the end walls, 9—9, of the breech-opening must be sufficiently far apart to permit the projectile to be fed sidewise into position, but when the projectile is in place in the bore 3 they do not prevent its discharge as 10 they are wholly out of the path of the projectile.

The projectiles to be fired are preferably embodied in a projectile strip, one element of which is a strip or tape, such as *s*, the 15 other main element being the projectiles. These projectiles may be of any suitable type adapted to be detached from the strip and discharged from the gun. In the construction shown they are illustrated as shell-like 20 projectiles in sliding engagement with the strip, they being illustrated here as slotted at their butt ends longitudinally to receive the strip edgewise. The saw-cuts or slots 10 in the projectiles *p* should be narrow enough 25 to enable the projectiles to obtain a fairly good hold upon the strip or tape and at the same time be readily slidable along said tape and also crosswise thereof. Sliding movement lengthwise of the tape is desirable 30 in order to position the projectiles readily in close succession in contact with one another, and sliding movement crosswise of the tape is essential in order to permit ready detachment and discharge of said 35 projectiles.

Any suitable means may be employed for feeding the strip *s* with its projectiles *p*, preferably crosswise of the gun, to bring said projectiles successively into the breech- 40 opening and into firing position in the bore of the gun. I have shown a rotary feed device for this purpose, which consists of a spindle or shaft, 11, having a handle, 12, at the rear end of the gun and carrying a 45 suitable reel or spool, 13, to which one end of the strip *s* is intended to be attached. Here the spindle and handle are both made from a single piece of wire and the reel is split and has a spring clamping sleeve for 50 securing the reel in fixed relation with the spindle 11, but in such a way that it will yield should excessive tension be put on the strip, as the result of jamming of a projectile or otherwise. Here the strip is in- 55 serted at one end in a slot, 14', in the sleeve, 14, and the tape is wound onto the reel and projectiles fed toward the breech-opening by turning the handle 12. At the other end of the strip a fixed stop 15 is shown which 60 may be about the same length as the projectiles, and this constitutes a back stop for the ammunition or projectiles attached to the strip *s*. This back stop is employed for the purpose of locating each projectile 65 positively in a fixed position lengthwise of

the strip, the first projectile placed on the strip being slid to position in contact with the stop 15 and successive projectiles attached to the strip being slid into contact with said first projectile and the succeeding ones respectively, so that all of the projectiles will be located by said back stop and by contact with one another in fixed positions along the strip *s*.

When the strip is fed by the turning of 75 the handle 12 to a point where the first projectile *p* comes in contact with the stop wall 8 of the breech-opening 6, it is then in position for firing. The projectile so positioned may be discharged from the gun by 80 any suitable firing means, such for example as a firing hammer or pin, 16, which in this case is movable to and fro in the rear end of the bore or way 3 through which the projectiles are to be discharged. An important 85 feature of the present invention is the employment of firing means controlled by the same element that controls the feeding of the strip. In other words the handle 12 here serves to feed the strip crosswise of 90 the gun to bring the projectiles successively to firing position and it also serves to bring about the operation of the hammer or pin 16. In this case the hammer or pin 16 is loosely connected to the upper end of a 95 strong spring, 17, suitably secured at the rear end of the open frame 4, below the breech end of the gun, and having a straight vertical part carrying the hammer adapted to be snapped back and forth to cause said 100 hammer to strike each positioned projectile a sharp blow which will drive the projectile out of the gun with considerable force. Here this straight portion of the hammer- 105 actuating spring 17 is drawn back by means carried by the wire forming spindle 11 and handle 12. In fact, this wire in the construction illustrated, forms also the element for turning back and releasing the hammer- actuating spring 17, said wire having a 110 coiled portion, 18, shaped to form a combined feed-screw and quick-let-off device by means of which the spring is drawn back at the proper point by the turning of the handle 12 and released a moment later, that is, just after a projectile is located in position in the bore 3 in the space between the 115 ends of the breech-opening 6.

It will be clear that by merely turning the handle 12 the projectile-strip will be fed 120 rapidly crosswise of the gun to bring the projectiles *p* successively to firing position, and the spring 17 with the hammer or firing-pin 16 will be rapidly drawn back and released to drive such positioned projectiles 125 in quick succession, substantially in a continuous stream, from the muzzle of the gun.

What I claim is:

1. A toy gun comprising a body having a way for the discharge of projectiles, a pro- 130

- jectile strip carrying detachable projectiles, means for driving the projectiles from the strip through the way by direct contact with the projectiles, and means for feeding the strip and actuating the driving means.
2. A toy gun comprising a body having a way for the discharge of projectiles, a projectile strip carrying detachable projectiles, means for driving projectiles from the strip through the way by direct contact with the projectiles, and means for feeding the projectiles to said way in a direction transverse thereof and for actuating the driving means.
3. A toy gun, comprising a body having a way for the discharge of projectiles, a projectile-strip carrying detachable projectiles, and means for feeding projectiles to said way in a direction transverse to the way and for driving projectiles from the strip through said way, said means including a hammer arranged to contact directly with the projectile.
4. A toy gun, comprising a body having a way for the discharge of projectiles, a projectile-strip carrying detachable projectiles, quick-acting means for feeding said strip to, and driving projectiles therefrom through, said way, said means comprising a combined feeding and firing handle, and a hammer arranged to contact directly with the projectile.
5. A toy gun comprising a body having a way for the discharge of projectiles, which way is intersected by a transverse breech opening for receiving projectiles, a projectile strip carrying detachable projectiles, means for driving said projectiles from the strip and through the way by direct contact with the projectiles, and means for feeding the projectiles to the breech opening and actuating the driving means.
6. A toy gun, comprising a body having a way for the discharge of projectiles which way is intersected by communicating transverse strip and breech openings of different dimensions in the direction of the length of the gun, a projectile-strip carrying detachable projectiles, and means for feeding said strip through said openings, to locate projectiles in said breech-opening and for driving projectiles from said strip through said way.
7. A toy gun, comprising a body having a way for the discharge of projectiles, a projectile-strip carrying detachable projectiles slideable on said strip and held in place by an end stop on said strip, and a feed device for feeding said strip.
8. A toy gun, comprising a body having a way for the discharge of projectiles, a projectile-strip carrying detachable projectiles,
- 5 60 65 70 75 80 85 90 95 100 105 110 115
- slotted to slide on said strip and held in place by an end stop on said strip, and a feed device for feeding said strip.
9. A toy gun, comprising a body having a way for the discharge of projectiles, a projectile-strip carrying detachable projectiles, and a rotary feed device for feeding said strip said device embodying a detachable reel for said strip.
10. A toy gun, comprising a body having a way for the discharge of projectiles, a hammer carried by a spring having a straight portion disposed substantially at a right angle to said way, and a rotary device for actuating said hammer said device comprising a single piece of wire bent to form a quick-let-off device co-operative with said spring and having its axis substantially parallel with that of said way.
11. A toy gun, comprising a body having a way for the discharge of projectiles, a transverse breech-opening and a transverse strip-opening of less length than the breech-opening, a projectile-strip carrying a plurality of detachable projectiles movable transversely through the breech-opening and strip-opening, and means for ejecting the projectiles through the way in the body.
12. A toy gun, comprising a body having a way for the discharge of projectiles and a breech-opening, a projectile-strip carrying detachable projectiles, means for moving the projectiles into the opening, and means for positioning the projectiles on the strip previous to their entry into the breech-opening.
13. A toy gun, comprising a body having a way for the discharge of projectiles and a breech-opening, a projectile-strip carrying a plurality of detachable projectiles, means for moving the projectiles into the breech-opening, and means engageable with the projectiles to successively position them in alignment with the before-mentioned way.
14. A toy gun comprising a body having a breech opening therein, a projectile strip movable transversely of the breech opening, projectiles movable transversely and longitudinally of said strip, a stop fixed to one end of the strip, and means engageable with the projectiles to successively position them within the breech opening and coacting with the stop to maintain the remainder of the projectiles in predetermined positions with relation to the strip.
